US0D1023029S

(12) **United States Design Patent** (10) **Patent No.:** **US D1,023,029 S**
Chang (45) **Date of Patent:** **** Apr. 16, 2024**

(54) **DISPLAY SCREEN OR PORTION THEREOF WITH A GRAPHICAL USER INTERFACE**

(71) Applicant: **Beijing Kuaimajibian Technology Co., Ltd.**, Beijing (CN)

(72) Inventor: **Weiyi Chang**, Beijing (CN)

(73) Assignee: **BEIJING KUAIMAJIBIAN TECHNOLOGY CO., LTD.**, Beijing (CN)

(**) Term: **15 Years**

(21) Appl. No.: **29/821,565**

(22) Filed: **Dec. 30, 2021**

(30) **Foreign Application Priority Data**

Jul. 2, 2021 (CN) 202130418178.9

CLAIM

The ornamental design for a display screen or portion thereof with a graphical user interface, as shown and described.

DESCRIPTION

FIG.1 is a front view of a first embodiment of a display screen or portion thereof with a graphical user interface showing the new design; and,

FIG. 2 is a front view of a second embodiment thereof. The outermost broken line rectangle illustrates a display screen or portion thereof and forms no part of the claimed design.

1 Claim, 1 Drawing Sheet
